UNITED STATES PATENT OFFICE.

TALBOT C. DEXTER AND HENRY HALLSTREAM, OF PEARL RIVER, NEW YORK; SAID HALLSTREAM ASSIGNOR TO SAID DEXTER.

SHEET-CALIPERING DEVICE FOR PAPER-HANDLING MACHINERY.

SPECIFICATION forming part of Letters Patent No. 749,037, dated January 5, 1904.

Application filed September 18, 1902. Serial No. 123,906. (No model.)

To all whom it may concern:

Be it known that we, TALBOT C. DEXTER and HENRY HALLSTREAM, both citizens of the United States, residing at Pearl River, in 5 the county of Rockland, State of New York, have invented certain new and useful Improvements in Sheet-Caliper Devices for Paper-Handling Machinery, of which the following is a specification.

- 10 The present invention is an improvement upon the sheet-caliper mechanism covered by Patent No. 663,672, granted December 11, 1900, to Talbot C. Dexter. In this Dexter patent the sheet-caliper device comprises,
- 15 essentially, a normally stationary rotatable caliper member, which is adapted to engage and operate a suitable device controlling the throw-out mechanism which is arranged to arrest the operation of the machine,
- 20 to which the device is applied. In the normal operation of a paper-handling machine equipped with this patented sheet-caliper device said rotatable sheet-caliper member is not affected by the passing sheets, be-
- 25 cause it is so set with relation to its co-operating member (between which members the successive sheets of paper pass) that the sheets will be allowed to move freely under said rotatable caliper member; but the moment
- 30 an abnormal thickness of sheets attempts to pass the rotatable caliper member, as in the case of two sheets passing from the machine at the same time, said caliper member will be frictionally engaged and rotated
- 35 sufficiently to actuate the device which releases the throw-out mechanism, resulting in the arrest of the operation of the feeding machine or other machine to which the mechanism is applied.
- 40 In the practical application of the sheet-caliper mechanism of the Dexter patent referred to the arrangement was such that the throw-out mechanism of the machine could operate only once during each rotation
- 45 of the controlling-shaft, which operation is timed to take place just after each sheet of paper starts from the machine. It sometimes happens, however, in the operation of paper-feeding machines that a second sheet of paper
- 50 will follow some little distance after the sheet

which is being fed off, so that by the time the double thickness of sheets reaches the caliper device the throw-out-controlling device has passed beyond the point when it will operate, and it is therefore impossible 55 to arrest the operation of the machine until the troublesome sheet has passed so far forward that it is liable to cause damage.

In our present invention we employ the normally stationary rotatable sheet-caliper member which forms a part of the Dexter device above referred to; but in place of the intervening controlling devices of the Dexter mechanism we employ a mechanism which is adapted to immediately arrest the operation 60 of the machine at any point in its operation, so that the machine will be instantly stopped whenever a double thickness of sheets passes the caliper member, no matter whether at the start of the operation of feeding a sheet 65 or at a later time during the operation of the machine. In accomplishing this result we arrange a trip finger or pawl in position above the rotatable caliper member to be moved thereby into engagement with a ratchet- 70 wheel which is mounted upon a constantly-driven shaft, said shaft being operated through the medium of suitable clutch mechanism which is capable of allowing the sudden stoppage of the shaft when it is engaged by 75 the caliper-operated pawl and also of actuating the throw-out mechanism of the machine.

In order that our invention may be fully understood, we will first describe the same with reference to the accompanying drawings 85 and afterward point out the novelty more particularly in the annexed claims.

In said drawings, Figure 1 is a detail longitudinal vertical sectional view of part of a paper-feeding machine, illustrating our invention applied thereto and showing the parts of the mechanism in their normal position while the machine is running. Fig. 2 is a similar view showing the parts in tripped position. Fig. 3 is a detail vertical transverse 90 sectional view illustrating the constantly-rotating controller-shaft and its clutch mechanism which actuate the throw-out mechanism of the machine. Figs. 4 and 5 are detail views of the clutch members.

We have illustrated our invention as applied to a paper-feeding machine; but it will be clear to those skilled in the art that the invention may readily be applied to any machine which is designed to operate upon sheets of paper which pass successively through it.

In the machine shown in the drawings the pile of paper P is shown in position to be fed to a folder, printing-press, ruling-machine, or other machine designed to operate upon the paper. This pile P is mounted upon an adjustably-supported table, which is not shown.

1 indicates the frame of the machine, upon which are mounted the operating parts of the feeder, which are not shown, since they do not form any part of our present invention.

10 is the main operating-shaft of the machine, to which is secured a large gear 11, meshing with an intermediate gear 12, journaled upon a stud 13 of the machine-frame 1. The gear 12 meshes with a smaller and narrower-faced gear 15, which is formed integral with the movable member of a clutch 25 which will presently be described.

A shaft 20 is mounted in suitable bearings in the machine-frame and carries a ratchet-wheel 25, which is located at or adjacent to the central longitudinal line of the machine. 30 A trip finger or pawl 30 is journaled to the machine-frame at 31 in position to engage the ratchet-wheel 25, said trip-finger having a downwardly-projecting weighted end 32, which rests directly behind an eccentrically-mounted pin 33, projecting from one face of the upper rotatable caliper member 35, so that when the member 35 rotates the trip finger or pawl 30 will be moved into engagement with the ratchet-wheel 25. This upper rotatable caliper member 35 is journaled in an arm 36, pivoted at 37 to the machine-frame and supported in the desired adjusted position by means of an adjustable limiting-screw 38, threaded through a lug 36^a of arm 36 and engaging a rigid lug 39 of the machine-frame. By adjusting the screw 38 the normally stationary upper caliper member 35 may be adjusted to a nicety with relation to the lower constantly-rotating caliper-wheel 40, which

50 is mounted upon the shaft 41, suitably journaled in the machine-frame. The outer end of the shaft 20 has pinned to it a coupling-collar 50, formed with integral radial lugs 51, which engage in the radial notches 52, formed 55 in the enlarged inner end of the sleeve 53, to detachably couple said sleeve to the shaft 20. The sleeve 53 is journaled in the bearing 16 and formed at its outer end with an enlargement or head 54. This head 54 constitutes

60 the fixed member of the main clutch. The outer face of the fixed main clutch member 54 is formed with radially-extending cam lugs or projections 55, which normally engage in the corresponding cam-recesses 56, formed in 65 the inner face of the movable main clutch member 48. This clutch member 48 is formed

with a tubular extension 58, which is journaled freely in the bearing 59, and the outer end of the tubular extension 58 is formed with angular clutch-teeth 60, which constitute one member of the auxiliary rotary clutch and are adapted to engage the corresponding clutch-teeth 61 of the other auxiliary rotary clutch member 62, freely journaled in bearing 59 in line with extension 58. Auxiliary 70 clutch member 62 is secured to the throw-out-operating disk 63, to which the throw-out-operating link 64 is eccentrically pivoted at 65. The clutch member 62 and disk 63 are free to move outwardly slightly when clutch 80 members 48 60 are forced toward them. Clutch member 62 is formed with an annular groove 66, in which engages a pin 67, projecting through slot 68 in bearing 59 and mounted upon a slide-bar 69. This slide-bar 69 is formed with slots 70, in which engage set-screws 71, threaded into the bearing 59. A spring 72 connects pin 73 of slide 69 with stationary pin 74 on bearing 59 to hold slide 69, pin 67, and the engaged 90 clutch member 62 in their normal inner position, as shown in Fig. 3 of the drawings. When clutch members 48 60 are forced outwardly, the clutch member 62 can yield sufficiently to insure clutch-teeth 60 effectively 95 interlocking with clutch-teeth 61. The clutch member 48 also carries a tube 80, which may be suitably secured thereto. Tube 80 is shown as threaded into member 48 and tubular extension 58 and is extended from member 48 into sleeve 53 of main fixed clutch member 54. A head or plug 81 closes the inner end of tube 80, and a rod 82 projects through a central opening in plug 81 and is formed at one end with an eye 83, through 105 which passes a pin 84 for securing rod 83 to the sleeve 53 of the fixed member of the main clutch. The outer end of rod 82 is threaded to receive adjustable head or nut 85, and surrounding rod 82 and confined between head 85 and plug 81 is a spring 86. This spring device is for the purpose of holding movable clutch member 48 normally in engagement with fixed clutch member 54 and at the same time allow relative movement 110 between the clutch members. The clutch member 48 has formed integral with it the gear 15, above referred to.

The link 64 is pivoted at its upper end 90 to the forward end of the rock-arm 91, which is keyed to a rock-shaft 92, suitably journaled in the machine-frame.

93 is a hand-lever for manually rocking the shaft 92. The rock-shaft 92 is operatively connected with any suitable throw-out mechanism arranged to arrest the operation of the machine when operated by the movement of rock-shaft 92, caused by the stopping of the rotation of controller-shaft 20 by the engagement of the caliper-operated trip-finger 30. 130 The throw-out mechanism is not shown in the drawings, but will be clear to those skilled

in the art. The said mechanism may be constructed as fully set forth in the above-named patent of Dexter, No. 663,672.

The operation of our improved sheet-caliper mechanism will be clear from the following description: As long as the sheets of paper pass singly from the machine they will move freely under the upper caliper member or wheel 35 without moving it; but as soon as an extra thickness of paper attempts to pass beneath the caliper-wheel 35, as when two sheets are moved from the pile at the same time, said wheel 35 will be rotated in the direction indicated by the arrow and will force the trip finger or pawl 30 into engagement with the ratchet-wheel 25. The shaft 20, carrying ratchet-wheel 25, is constantly rotating while the machine is operating, motion being transmitted to it through the gearing 11, 12, 15, and 20 the main clutch members above described. When the pawl 30 engages ratchet-wheel 25, shaft 20 will be immediately stopped, and as the movable main clutch member 48 is positively driven by the gearing referred to said clutch member 48 will continue to rotate for a partial revolution until the cam-faces of the recesses 56, riding upon the projections 55, force the tubular extension 58 outwardly to throw auxiliary clutch-teeth 60 into engagement with clutch-teeth 61, the result of which will be the rotation of throw-out-operating disk 63, the pulling down on link 64 and arm 91, and the rocking of shaft 92 for throwing out the main clutch of the machine. In this way the machine will be quickly stopped before the objectionable thickness of paper has gotten sufficiently beyond the caliper-point to cause any damage. By the time the motion of the machine has been stopped the movable member 48 of the main clutch will have made half a revolution more than the fixed member 54 of the main clutch, with the result that the projections 55 will again slip into engagement with recesses 56, as in the normal clutched position, and the auxiliary clutch-teeth 60 will be disengaged from clutch-teeth 61 in readiness for starting up the machine again. Our improved mechanism will arrest the operation of the machine at any point in its operation that the objectionable thickness of paper appears at the caliper.

Having thus described our invention, the following is what we claim as new therein and desire to secure by Letters Patent:

1. In combination with a machine through which sheets of paper are passed, and suitable throw-out mechanism adapted to arrest the operation of said machine, of a sheet-caliper device adapted to be operated by an abnormal thickness of sheets, a rotary shaft, means actuated by said caliper device for arresting the movement of said shaft, and means operated by the stopping of said shaft for actuating the throw-out mechanism.

2. In combination with a machine through

which sheets of paper are passed, and suitable throw-out mechanism adapted to arrest the operation of said machine, of a normally stationary rotatable sheet-caliper device 70 adapted to be operated by an abnormal thickness of sheets, a rotary shaft carrying a ratchet-wheel, means operated by the stopping of said shaft for actuating the throw-out mechanism, and a tripping finger or pawl 75 adapted to be operated by said rotatable sheet-caliper device to engage the ratchet-wheel and arrest the rotation of said shaft, substantially as set forth.

3. In combination with a machine through 80 which sheets of paper are passed, and suitable throw-out mechanism adapted to arrest the operation of said machine, of a sheet-caliper device, a rotary shaft, driving mechanism including clutch members, one of which is 85 fixed to said shaft and one of which is movable relatively to the fixed member, and means thrown into operation by the relative movement of the clutch members for actuating the throw-out mechanism, and means operated 90 by the caliper device for arresting the movement of said shaft, substantially as set forth.

4. In combination with a machine through which sheets of paper are passed, and suitable 95 throw-out mechanism adapted to arrest the operation of said machine, of a sheet-caliper device, a rotary shaft, driving mechanism including clutch members, one of which is fixed to said shaft and one of which is movable 100 relatively to the fixed member, a spring device connecting the movable clutch member with the fixed clutch member, means thrown into operation by the movement of the movable member for actuating the throw-out mechanism, and means operated by the 105 caliper device for arresting the movement of said shaft, substantially as set forth.

5. In combination with a machine through 110 which sheets of paper are passed, and suitable throw-out mechanism adapted to arrest the operation of said machine, of a sheet-caliper device, a rotary shaft, a main fixed clutch member upon said shaft, a main movable clutch member yieldingly engaging said fixed 115 clutch member, means operating through said main clutch members for rotating said shaft, an auxiliary clutch thrown into operation by the movement of the movable clutch member, means connecting said auxiliary clutch with 120 the throw-out mechanism, and means operated by the caliper device for arresting the movement of said shaft, substantially as set forth.

6. In combination with a machine through 125 which sheets of paper are passed, and suitable throw-out mechanism adapted to arrest the operation of said machine, of a sheet-caliper device, a rotary shaft, a main clutch member fixed to said shaft, a second main clutch 130 member movably mounted upon said shaft in operative relation to the fixed member, a mov-

able auxiliary clutch member fixed to the movable member of the main clutch, a rotatable disk operatively connected with the throw-out mechanism, an auxiliary clutch member connected with said disk and mounted in operative relation to the auxiliary clutch member upon the movable main clutch member, and means operated by the caliper-

ing device for arresting the movement of said shaft, substantially as set forth.
